Edward F. Marrs, Inventor

UNITED STATES PATENT OFFICE.

EDWARD F. MAERS, OF SAN DIEGO, CALIFORNIA.

AUTOMOBILE-SIGNAL.

1,317,178.

Specification of Letters Patent. Patented Sept. 30, 1919.

Application filed November 24, 1916. Serial No. 133,220.

To all whom it may concern:

Be it known that I, EDWARD F. MARRS, a citizen of the United States, residing at San Diego, in the county of San Diego and State of California, have invented certain new and useful Improvements in Automobile-Signals, of which the following is a specification.

This invention has relation to signaling devices for motor vehicles, or the like, and has for its object to provide signaling devices in duplicate, each adapted for connection to the motor vehicle at the forward and rearward portions thereof, and embodying a movable element in the nature of a pointer, operable by electrically controlled means whereby the driver of the vehicle may cause the pointers to be directed simultaneously toward the right or the left to indicate to the occupants of approaching or following vehicles, the direction in which the vehicle bearing the signals is about to turn.

Another object of the invention is to provide signaling devices for automobiles having the above named characteristics, and embodying a novel arrangement of a stationary energizable field magnet, and an energizable armature movable adjacent thereto, and means controllable by the driver for actuating said elements simultaneously and in a proper manner for the purpose of causing movement of the armature in either direction, according to the direction in which the energizing current is admitted to the elements whereby a pointer connected to said armature may be directed toward the right or the left.

In addition to the foregoing, my invention comprehends improvements in the details of construction and arrangement of the parts without departing from the spirit of the invention or the scope of the appended claim.

In the accompanying drawings in which similar and corresponding parts are designated by the same characters of reference throughout the several views in which they appear:

Figure 1, is a view in side elevation of a motor vehicle, illustrating the application thereto of my invention.

Fig. 2, is a vertical longitudinal section taken through a signaling device constructed after the manner of my invention.

Fig. 3, is a diagrammatic view setting

forth the wiring of the devices, the controlling switch and interconnected wiring whereby the devices are actuated, and

Fig. 4, is a diagrammatic view illustrating the operation of the device.

With reference to the drawings, 10 indicates a cylindrical casing adapted to be disposed in an upright position, and which is closed by a permanently fixed head 11, at 65 its lower end, and a removable cover 12 at its upper end. Within the casing is field magnet 13 composed of a plurality of annular laminations having inwardly and oppositely disposed extensions forming pole 70 pieces 14, and 15. The laminations are held in alined relation through the medium of bolts 16 said bolts serving also to secure in place a transverse strip 17, provided at its intermediate portion with a bearing 18. 75 The lower end 11 of the cylindrical casing is formed with a bearing 19 in alinement with the aforesaid bearing 18, and an armature designated generally at 20, is mounted upon a shaft 21 which extends through 80 said bearings, and with its upper end extended beyond and exteriorly of the removable cap 12 of the cylinder. The armature 20 is of the double opposed pole type, the poles thereof being indicated at 22 and 23, 85 and the wiring of said armature consists of a single strand which is secured in an electrical connection at 24 to one of the pole pieces of the armature, while the opposite end is electrically connected to a commutator 90 25 mounted upon the shaft 21 interiorly of the casing and upon the lower end of said shaft. The commutator 25 is in the nature of a continuous ring or annular metallic member insulated from the shaft through 95 the medium of an insulated bushing 26. Extending radially, is a bushing 27 insulated from the casing through the medium of an insulated bushing 28, the metallic bushing 27 being hollow for the reception of 100 a brush member 29 which is slidably mounted within the bushing 27 and is adapted to engage at one end the circuit of the commutator 25, the bushing 27 at its opposite end being provided with a plug 30 having 105 threaded engagement within the bushing, and a spring 31 is interposed between the inner end of said bushing and said plug whereby said plug may be held in engagement with the commutator.

A pointer or semaphore is provided which is preferably formed of sheet metal and has

the outline of a hand with the index finger extended, said pointer being indicated at 32, and provided with a vertically extending rod 33 provided with a socket 34 at its 5 lower end in which to receive the projecting end of the shaft 21. A set screw 35 having threaded engagement in the lower end of the rod 33 is adapted to engage the shaft to retain the pointer in fixed relation. The 10 aforesaid connecting strip 17 is extended beyond the side of the casing exteriorly thereof to form an extension 36 and which is formed with an aperture to receive the vertical stud 37, secured to the tubular extension through the medium of nuts 38 having threaded engagement with the stud and disposed against the upper and lower sides of the extension whereby the stud is held in permanent fixed relation. A coil 15 20 25 spring 38' is connected at one end to the aforesaid stud 37 and at its opposite end to the projecting end of the shaft 21, in such a manner that a rotative movement of said shaft in either direction will place the spring under strain thereby urging the shaft toward its former position.

The pole pieces 14 and 15 of the field magnet are each provided with a winding indicated respectively at 40 and 41, and one 30 of the terminals of each winding is connected by means of a conductor 42. As before stated, one of the devices is mounted at each end of the motor vehicle in suitable brackets 42' and one of the field windings 35 of each device is connected through the medium of a conductor 43; the terminals of the other windings 41 are connected through the medium of a conductor 44. A double pole reversing switch indicated at 45 is 40 mounted upon the steering column 46 of the vehicle and is provided with the usual central opposite contacts 47 and 48. The conductor 43 is connected to the contact 47 by the conductor 53 and the contact 48 is connected to the source of current 59 by a lead 54 which has one terminal joined to one of the terminals of the battery. The opposite terminal of the battery is connected to a conductor 55 which is joined to the conductor

44. A lead 58, from the conductor 56 is 50 connected to the contact 49 of the switch and the opposite contact 50 of the switch is connected by a lead 60 to the conductor 57. Directly opposite to the contacts 49 and 50, on the reversing switch are the contacts 51 and 52 electrically connected to the contacts 50 and 49 respectively, in the usual manner. The conductor 56 connects the brushes 29 together and the conductor 57 connects the casings of the device and since 60 the armature coil is connected with the armature pole, the armature coil will thus be grounded through the casing of the device. It will be obvious that reversing of the switch 45 will cause a reversal of the current 65 in the connecting conductors 56 and 57. It will be noted that the reversal of current will occur only in the armature.

Having thus described my invention what I claim as new and desire to secure by Letters Patent is:—

An electrically operable signal for automobiles, including a cylindrical casing, a bearing provided at one end thereof, a circular laminated field magnet mounted 75 within the casing, and having a pair of opposed pole pieces, a strip mounted to extend diametrically across said field magnet, said strip having an extension at one end, a bearing mounted on said strip, a shaft 80 mounted in the bearing, a radially movable brush mounted in the casing in insulated relation thereto, a plain ring commutator mounted on the shaft for engagement by said brush, an armature winding having 85 one terminal connected to the ring and the other grounded to the shaft, a stud mounted on the extension of the strip, a coil spring having one terminal connected to the stud and the other rigidly connected to the shaft, 90 and an indicating hand mounted on the shaft.

In testimony whereof I affix my signature in presence of two witnesses.

EDWARD F. MARRS.
